Patented Apr. 20, 1971

220,476

HANDRAILING

William J. Horgan, Jr., Pittsburgh, Pa., assignor to
Blumcraft of Pittsburgh, Pittsburgh, Pa.

Filed July 2, 1969, Ser. No. 18,032

Term of patent 14 years

Int. Cl. D25—01

U.S. Cl. D13—7

FIG. 1

FIG. 2

Des. 220,476

PAGE 2

FIG. 3.

FIG. 5.

FIG. 6.

FIG. 4.

FIG. 7.

FIG. 1 is a perspective view taken from the left of a handrail embodying my new design;

FIG. 2 is a top view of the handrail shown in FIG. 1;

FIG. 3 is a front view of the handrail shown in FIG. 1;

FIG. 4 is a bottom view of the handrail shown in FIG. 1;

FIG. 5 is a section taken as indicated by the lines and arrows 16—16 in FIG. 3;

FIG. 6 is a back view of the handrail shown in FIG. 1; and

FIG. 7 is a right side view of the handrail shown in FIG. 1.

The mounting surfaces shown in broken lines form no part of the design and are shown to illustrate environment only.

I claim:

The ornamental design for a handrail, as shown and described.
